UNITED STATES PATENT OFFICE

THEODORE BIRKENMAIER, OF ST. LOUIS, MISSOURI, ASSIGNOR TO W. N. MATTHEWS CORPORATION, OF ST. LOUIS, MISSOURI, A CORPORATION OF MISSOURI

ANCHOR

Application filed May 31, 1928. Serial No. 281,949.

This invention relates to anchors, and with regard to certain more specific features to helical earth anchors and wrenches therefor.

Among the several objects of the invention 5 may be noted the provision of a stronger helical anchor adapted to be driven home or retrieved by turning it with a wrench; and the provision of an anchor of the class described having no extraneous driving lugs or the like 10 which are difficult to properly manufacture. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

20 In the accompanying drawings, in which is illustrated one of various possible embodiments of the invention,

Fig. 1 is a side elevation showing the anchor and wrench therefor in driving position;

Fig. 2 is a plan view of the anchor, certain dotted lines showing the applied position of a wrench;

Fig. 3 is a side elevation of the wrench;

30 Fig. 4 is a plan view of the wrench shown in Fig. 3; and

Fig. 5 is an enlarged section showing a connection between the anchor and the wrench and is taken on line 5—5 of Fig. 1.

35 Similar reference characters indicate corresponding parts throughout the several views of the drawings.

Referring now more particularly to Fig. 1 of the drawings, there is illustrated at numeral 1 a shank pointed at 3 for piloting purposes and provided with an integrally cast helical flange 5. The shank is provided with a threaded recess 7 at its upper end for removably receiving a threaded rod 9, the latter comprising a guy rod which is adapted to be provided at its upper end with suitable cable holding means such as an eye or the like.

Heretofore hollow wrenches have been provided to slip over the rod 9, said wrenches

having been provided with either sockets at their lower ends to engage a polygonal upper end of shank 1 or sockets having slotted sides for engagement with lugs or the like on shank 1. The former method had the disadvantage 55 that under heavy torque the socket would be split open. The difficulty with the latter method was that a lug small enough to eliminate cutting away an excessive amount of the socket had a tendency to break. Furthermore, such lugs were relatively expensive to cast inasmuch as a floating shape was required in the molding process.

The present invention eliminates all of the above disadvantages. It is effected by providing an opening 11 through the helical flange 5 near its upper end and next to the upper end 13 of the shank 1 (see Fig. 2). This opening does not substantially weaken the flange inasmuch as it is spaced at some 70 distance from the rear edge 15 of said flange.

The wrench comprises a hollow square or other polygonal tube 17 having a cylindrical socket 19 at its lower end, the socket being of such diameter as to rotatably fit the upper 75 cylindrical end of the shank 1. On one side the socket 19 is provided with a recess 21 having a sloping upper edge 23 adapted to cooperate with the sloping upper surface 25 of the flange 5 between the opening 11 and the edge 15. The sides of the recess 21 are provided with retaining lugs 27 at their lower ends.

A removable wrench handle 29 is provided for the square portion 17 of the wrench. The 85 operation of the device is as follows:

The shank 1 is threaded with a guy rod 9. The wrench shown in Fig. 3 is then slipped over the guy rod 9 and the socket portion 19 caused to surround the upper end 13 of the 90 shank 1. The handle 29 is then applied and the wrench manipulated so that the recess 21 is positioned over the region 25 between the opening 11 and the edge 15. This results in the trailing portion 31 of the socket next to 95 the opening 21 being positioned in the recess 11, while the leading portion 33 next to the opening 21 is positioned next to the trailing edge 15 of the flange 5 (see Fig. 1). The sloping upper edge 23 of the opening 21 en- 100

gages with a sloping upper surface 25 of the flange 5.

The engagement between the anchor and wrench above set out is exceedingly solid. 5 Upon turning the handle 29 clockwise, the leading edge 33 of the socket 19 drives the edge 15 of the helix 5 to set the anchor. Retrieving of the anchor may be effected by a counter-clockwise movement which causes engagement between the trailing portion 31 of 10 the wrench with one edge of the opening 11. The lugs 27 ensure that the wrench will not ride up during a twisting operation.

It will be seen that this invention eliminates 15 the lugs that have been used heretofore for the wrench engaging purposes. There is no tendency to split open the socket 19 as when it is used with a polygonal head on the shank 1. Furthermore, the present anchor 20 is much easier to construct, inasmuch as the opening 11 may be cored with less difficulty than was had in casting on a lug or lugs. By placing the opening 11 directly in the helical flange 5, it is clear that maximum simplicity 25 of construction is effected.

In Fig. 5 the shank 1 is shown with a recess 28 around the end of the threaded hole which receives the threaded rod. The purpose of this recess is to form a rim to limit the amount 30 of bending the rod 9 can do at the weak threaded section at the end of such of the threads as can never be quite screwed home. Reference is here made to the last imperfect threads always obtained with a die. Any 35 further bending of the rod after a certain amount due to side load is effected only where the rod touches the rim of the recess, which rim is positioned at a stronger unthreaded portion of the rod. Excessive bending then 40 does not tend to break the rod at the exposed threads.

In view of the above, it will be seen that the several objects of the invention are achieved and other advantageous results attained.

45 As many changes could be made in carrying out the above constructions without departing from the scope of the invention, it is intended that all matter contained in the above description or shown in the accompanying drawings shall be interpreted as illustrative and not in a limiting sense.

I claim:

1. In an anchor, a shank, a helical web having an opening therethrough for wrench 55 engaging purposes and having a trailing edge adapted to be engaged by said wrench for driving purposes.

2. In an anchor, a shank, a helical web having an opening therethrough for wrench 60 engaging purposes and having a trailing edge adapted to be engaged by said wrench for driving purposes, the engagement of the wrench with said opening being for retrieving purposes.

65 3. In combination, an anchor having an

interiorly threaded portion, a guy rod threaded therein, a fixed rim portion on the threaded portion spaced from the upper end of said threaded portion adapted to engage said rod upon the rod bending.

4. In an anchor, a shank, a helical web having a single elongate opening therethrough for wrench engaging purposes, said opening being so arranged with respect to said shank that one side of the shank forms a side of the 75 opening.

5. In combination, an anchor having an interiorly threaded portion, a guy rod threaded therein, an integral rim portion formed on the threaded portion and spaced from the guy rod but being adapted to engage said rod upon bending of the rod.

6. A wrench for anchor driving purposes which comprises a hollow polygonal tube, a socket at the end of said tube adapted to engage the shank of an anchor to be driven, and a recess in the wall of said socket adapted to cooperate with a flange on said anchor, said recess having a sloping upper edge and at least one retaining lug on a side.

In testimony whereof, I have signed my name to this specification this 28th day of May, 1928.

THEODORE BIRKENMAIER.
